UNITED STATES PATENT OFFICE.

ARTHUR TREVOR DAWSON, OF WESTMINSTER, LONDON, AND JAMES HORNE, OF BARROW-IN-FURNESS, ENGLAND, ASSIGNORS TO VICKERS LIMITEL, OF WESTMINSTER, ENGLAND.

CONTROL SYSTEM FOR GUN-MOUNTINGS AND OTHER MECHANISM.

1,143,948.

Specification of Letters Patent. Patented June 22, 1915.

Application filed July 12, 1912. Serial No. 708,964.

To all whom it may concern:

Be it known that we, ARTHUR TREVOR DAWSON, knight, and JAMES HORNE, both subjects of the King of Great Britain, residing, respectively, at Vickers House, Broadway, Westminster, in the county of London, England, and Naval Construction Work, Barrow-in-Furness, in the county of Lancaster, England, have invented certain new and useful Improvements in or Relating to Control Systems for Gun-Mountings and other Mechanism, of which the following is a specification.

This invention relates to control systems for gun mountings and other mechanism.

In control systems "hunting" gear has been employed in conjunction with a power driven member forming part of the mechanism to be driven, and with a member which is actuated electrically from a distance but is incapable of itself exerting any appreciable force beyond that which is necessary to operate a relay for bringing the motive power into action. When the electrically actuated member is moved out of alignment or coincidence with a neutral point on the other or power driven member, an electric circuit is closed through suitably arranged contacts forming part of the two members and energizes the relay which brings into operation a motor for driving the mechanism and the said power driven member, such operation continuing so long as the circuit remains closed, *i. e.*, until the neutral point of the power driven member regains its position of alignment or coincidence with the electrically actuated member.

According to this invention the aforesaid members are so constructed and arranged that when, on the completion of an electric circuit through the aforesaid contacts, the relay moves the valve, rheostat or other control device appertaining to the motor of the mechanism to be driven, the relay will at the same time open the electric circuit and thus stop its own movement, the extent of the relay movement required to thus break the circuit depending on the amount of displacement or "lag" created between the power driven member and the electrically actuated member. Conversely as the two members move into realinement the electric circuit through the relay will again be closed and the relay will move in the oppo-

site direction and will gradually shut off the power to the motor driving the mechanism as the position of coincidence between the members is approached, so that when this position is reached the supply of power will be quite cut off by the relay. This interdependence of the movement of the relay and the relative displacement of the electrically actuated member and the power driven member insures that the starting and stopping of the motor will take place in a gentle manner and without undue oscillation of the control device when the aforesaid members assume their position of coincidence or neutrality to bring the motor to rest. For this purpose the contact surfaces of the power driven member are separated from each other by a suitably inclined or curved insulating strip or gap and the contact on the electrically actuated member is caused to be displaced laterally by the action of a relay when movement is imparted to the said member from the transmitting station, the extent of the lateral displacement depending on the degree of movement transmitted to the control device by the relay. By these means the amplitude of movement given to the control device and the length of time expiring before the said device resumes its normal position are proportional to the relative displacement or "lag" that exists between the two members.

Where the power which the electrically actuated member is capable of exerting is sufficient, the inclined or curved insulating strip or gap on the drum may be replaced by a cam groove of similar shape in which a pin or roller on the end of the electrically actuated member is adapted to engage. The movements of the controlling gear would then be in exact accordance with the path of the cam groove.

In order to avoid the necessity of laterally displacing the electrically actuated member as aforesaid the contact rings on the power member or members may be divided into a number of segments each of which is electrically connected to a contact finger or the like that is adapted to bear on one or other of two contact plates connected to the control device, the said contact plates forming part of the electrical connections with the relay.

In the distant control of mechanism such

- as turret training and gun elevating mechanism, it is often necessary that the said gear shall be displaced from the position it has received from the transmitting station in order to correct the displacements for such conditions as the varying muzzle velocities of the gun, and in the case of training mechanism to correct the displacements for the "separation" or distance of the gun from its distant sighting station. In order that these corrections may be effected in an improved manner, we provide means for displacing the motor or other operating device of the electrically actuated member about the axis of rotation of the said member. For this purpose the motor or other operating device of the electrically actuated member is mounted on a frame that can be angularly displaced about the axis of rotation of the electrically actuated member and the power driven member. By fixing a pointer to the frame we can set the latter at any point on a scale engraved in terms of the particular correction we wish to apply. We may if desired employ other means for swinging the frame carrying the motor of the electrically actuated member, about the axis of rotation of the said member.
- 30 In order that the said invention may be clearly understood and readily carried into effect we will describe the same more fully with reference to the accompanying drawings, in which:
- 35 Figure 1 is a sectional elevation showing one constructional form of the apparatus embodying our invention. Fig. 2 is a detached view of the power driven member, showing a modified arrangement of the contact surfaces thereon. Fig. 3 is a view similar to Fig. 1, showing a modified form of apparatus for enabling the electrically actuated member to make more than one revolution with respect to the power driven member. Fig. 4 is an elevation showing a modified form of apparatus, that is used when two receiving step-by-step motors or other operating devices are employed for working the electrically actuated member. Fig. 5 is a sectional elevation showing a modified form of the apparatus illustrated in Fig. 4. Fig. 6 is a diagram showing the electrical connections of the arrangement illustrated in Fig. 5. Fig. 7 is also a view similar to Fig. 1 showing a convenient arrangement of the motor mounted on an angularly displaceable frame.
- 40 In all these figures like letters of reference indicate similar parts.
- 45 A is the power driven member, B the electrically actuated member which is shown as being driven by a step-by-step electric motor B^x operated from the transmitting station, and C the control device of the motor used for driving the mechanism, the

said motor being in the examples illustrated intended to be driven by hydraulic power.

a represents the insulating strip or gap separating the contact surfaces a' , a^2 on the power driven member A, and b^x , b'^x represent the contacts forming part of the metal contact plate or bridge piece b on the electrically actuated member B.

In the examples shown in Figs. 1 to 4 the power driven member A is in the form 75 of a drum provided on its periphery with the contact surfaces a' , a^2 which comprise rings or strips of metal so formed that a part of the insulating gap a between them is at an inclination to a circumferential line 80 on the drum. The said drum is mounted on a shaft A^x having a pinion A' which forms part of the gearing connected to the mechanism to be driven, which may be the elevating or training gear of a gun, the said 85 pinion A' being driven by the hydraulic motor. The periphery of the said drum is furnished, in addition to the aforesaid two contact rings a' , a^2 , with a third ring a^3 for supplying current to the contact b^x ; the 90 other contact b'^x is adapted to bear upon either of the rings a' , a^2 or upon the insulated gap a as will be hereinafter described.

The electrically actuated member B is mounted on a spindle B' driven through a 95 spur wheel b' engaging with an elongated pinion b^2 on the shaft of the step-by-step motor B^x which is actuated from the transmitting station. The said spindle is arranged co-axially within the shaft A^x and 100 is adapted to move axially as well as revolve, and when, as is intended in the example shown, an hydraulic motor is used for driving the mechanism, this spindle is connected by means of an oscillatory lever C' 105 to the stem of a control valve (constituting the aforesaid control device C) for the hydraulic motor. The said lever oscillates about a pivot c^o which is adjustable in a slot in the lever so that the ratio of movement between the spindle B' and the control C can be varied if desired.

Referring more particularly to Fig. 1, each of the rings a' , a^2 , a^3 on the drum A is electrically connected with slip rings a'^x , a^{2x} , a^{3x} on the rear face of the drum, of which a'^x , a^{2x} are connected to two electromagnets or solenoid coils D D' constituting, with a plug valve v operated thereby, the aforesaid relay for causing the control valve C 115 to be moved. The ring a^{3x} is connected to the source of electric supply. The said magnets or coils, when energized, operate an armature or core D^x , the direction of movement of which depends upon the particular contact ring with which the contact b'^x is in electrical connection. The said armature or core is shown as formed with rack teeth that gear with a pinion on the spindle d of the plug d' appertaining to a cylinder d^2 in 120 125 130

- which is disposed a ram c' formed on the stem c of the control valve C , the end of the cylinder nearest the valve C being supplied with motive fluid under constant pressure.
- 5 In accordance with the direction in which the armature or core is displaced by the magnets or coils, the plug valve d' is moved to place the rear end of the cylinder to pressure or to exhaust, thereby causing a movement in one or other direction of the ram c' on the stem of the control valve C , and moving the latter to admit pressure fluid to the motor for driving the elevating or training mechanism and the aforesaid 10 drum A .
- The aforesaid neutral point of the insulating gap a is in the center of the inclined portion thereof, and when the contact b'^x bears upon this point (as shown in the 15 figures) the parts are at rest with the gun elevated or trained to a position corresponding to the elevation or training angle transmitted to the step-by-step motor B^x . When the electrically actuated member B is angularly displaced from the transmitting station as aforesaid its contact b'^x is moved from the said neutral position on to one or other of the two contact rings a' , a^2 of the 20 drum A according to the direction of movement imparted to it; assuming that the said member is moved to place the contact b'^x on the ring a^2 , the solenoid D is accordingly energized, and the plug valve d' moved so that the space on the right of the ram c' is 25 placed to pressure, with the result that the control valve C is displaced longitudinally toward the left and admits fluid pressure to the hydraulic motor for driving it in the required direction. This movement of the 30 valve C longitudinally displaces the spindle B' of the electrically actuated member to the right through the lever C' , with the result that the said member and its contact are shifted transversely to the drum A in the 35 opposite direction to the opening movement of the control valve.
- The electrically actuated member B is intended, in actual practice, never to be any considerable angular distance in advance of 40 the neutral point (i. e. the center of the inclined portion of the gap a) of the drum A , and the said member does not therefore become angularly displaced to a position beyond the ends of the inclined portion of the 45 insulating gap a ; consequently within these limits the amount of movement given to the control valve C is in proportion to the relative displacement or "lag" between the member B and the drum A as aforesaid.
- 50 Outside these limits however the valve is always completely opened.
- The transverse movement of the electrically actuated member does not move the contact b'^x out of engagement with the ring a^2 but returns the contact b'^x to the insulating
- strip or gap A . The supply of current to the solenoid D of the relay is then immediately cut off and the aforesaid plug valve d' is centered by suitable means, such as springs acting on the toothed armature or core D^x of the solenoids, and the control valve C is thus retained in the open position to which it has been moved. The hydraulic motor is thus set in motion and at the same time imparts angular movement to the drum A thereby bringing the other contact ring a' beneath the contact b'^x . The other solenoid D' of the relay is then energized and the plug valve d' actuated in the opposite direction to that aforesaid, with the result that the space on the right of the ram c' is placed to exhaust so that the fluid pressure constantly acting in the space at the left of the ram operates to move the control valve C to the right, i. e., toward its closed position, this movement continuing (without however being of sufficient extent to effect the closing of the control valve and consequently without stopping the movement of the drum A) until the contact b'^x has been returned transversely to a position on the inclined portion of the insulating strip or gap a .
- The further movement of the drum A again brings the contact ring a' beneath the contact b'^x and through the intervention of the solenoid D' of the relay again moves the plug valve d into a position to open the space on the right of the ram c' to exhaust. The control valve is thus caused to again move toward the right (i. e. toward its closing position) and in so doing causes the contact b'^x to again bear upon the insulating gap a . The further movement of the valve is thus prevented in the manner already described. These successive increments of movement of the control valve toward the closing position are continued until the contact b'^x reaches the center or neutral point of the aforesaid inclined portion of the insulating strip or gap a , whereupon the valve C is completely closed and the motor is finally brought to rest without any reversal and consequently without any oscillatory movement of the hydraulic motor and the elevating or training gear. The path traced on the drum by the contact b'^x is an undulating curve or zigzag line the mean of which is a line parallel to the insulating strip or gap.
- By suitably varying the degree of inclination of the inclined portion of the insulated strip or gap a , the valve may be caused to move any desired amount for a particular extent of "lag" or displacement between the two members, the valve movement varying in accordance with the inclination of the said gap. Thus with a gap which is only slightly inclined to a circumferential line on the drum, the valve movement in relation to the "lag" is smaller

120
125
130

than is the case with a gap arranged at a considerable inclination.

The center or neutral portion of the insulating gap on which the contact b^x of the 5 electrically actuated member B normally rests may, as shown in Fig. 2, be formed with a part running nearly parallel to the axis of the drum A, the inclination being in the same direction as that of the main inclined portion of the gap a . By this means 10 when the contact b^x is angularly displaced it will quickly reach the contact ring a' or a^2 (according to the direction of movement) and thus cause a quick movement of the 15 valve C from the central position to occur and at once take up the lap of the valve.

Fig. 3 shows a constructional form of the invention in which the electrically actuated member B is adapted to make more than one 20 revolution relatively to the drum A. In this example we provide a second or auxiliary drum A^o that is driven at a slower speed than the drum A, by means of toothed rings a^x , a^o on the drums A, A^o respectively 25 and interposed toothed wheels a^{xx} , a^{oo} . We also provide an auxiliary electrically actuated member B^o on a spindle b^o disposed within the spindle B' of the main electrically actuated member B, the said spindle b^o 30 being driven at a reduced speed by means of toothed wheels from the spindle B' . The said auxiliary member B^o has two contacts B^{oo} , B^{ox} , the former of which is adapted to bear against one or the other of two insulated contact pieces a^o' , a^{o2} on the auxiliary drum A^o or against an insulating gap 35 between them, and the other B^{ox} against the aforesaid supply ring a^3 of the drum A. The said contact pieces a^o' , a^{o2} are connected to insulated slip rings a^{o4} respectively, which are in circuit with the aforesaid solenoids D', D as shown. When the contact b^x lies on the center or neutral point of the inclined part of the insulating 40 gap a the contact B^{oo} of the auxiliary member B^o lies on the insulating gap between the two contact pieces a^o' , a^{o2} . When the amount of relative angular displacement or "lag" between the electrically actuated 45 member B and the drum A exceeds a certain amount, the contact pieces a^o' , a^{o2} , on the slow auxiliary drum A^o operate to maintain the supply of current to the particular solenoid that has previously been energized 50 through the intervention of the drum A and the contact b^x of the electrically actuated member B.

It should be understood that the width of the gap between the contact pieces a^o' , 55 a^{o2} should be such that it corresponds to the movement of the member B^o during the time that the member B is making half a revolution, so that the member B^o makes contact just before the member B has made 60 its half revolution, with one or other of the

contact pieces a^o' , a^{o2} which then maintains the supply of current to one or other of the solenoids D', D as aforesaid. The shape of the contact rings a' , a^2 is such that if the member B makes a half revolution 70 to either side of the central portion of the gap a , the contact b^x would pass from whichever of the rings a' , a^2 it was bearing against into contact with the other ring.

In order to prevent this last mentioned contact ring supplying current to the non-energized solenoid when the electrically actuated member B has made half a revolution relatively to the said drum as above stated, the spindle d of the aforesaid plug valve d' is, in the example shown, provided with a rotary switch d^3 that automatically breaks the circuit between the non-energized solenoid and its contact ring on the drum A. By this means after a certain amount of "lag" has taken place the control of the energized solenoid rests with the auxiliary drum A^o and the auxiliary member B^o , the drum A and its electrically actuated member B only coming into action when the auxiliary drum and its member have been brought into approximate alignment, i. e., returned to the position in which the contact B^{oo} just rests on the insulating gap between the contact pieces a^o' , a^{o2} . The drum 85 A and its member B then take over the control of the solenoid and finally become aligned, i. e., the contact b^x reaches the central or "neutral" point of the inclined portion of the gap a as above described, and the mechanism comes to rest with the contact B^{oo} resting on the center of the gap between the contact pieces of the drum A.

In the example shown in Fig. 4 two switches (one of which transmits large increments of range or bearing as set forth for example in the specification of the British Patent No. 11019 of 1911) are used at the transmitting station, and two motors B^x , B^{xx} , at the receiving station, connected to the spindles of the members B, B^o . Of these the motor B^{xx} and the member B^o appertain to the switch transmitting the larger increments. In this arrangement no gearing is employed between the members B, B^o , as the ratio 115 of the movement of the motors is the same as that of the transmitting switches.

In the foregoing arrangements the control valve C, the hydraulic cylinder d^2 and its plug d' may be replaced by a control switch 120 and solenoid where the elevating or training gear is driven by electric power.

Although we have described the contact rings or strips as being on the periphery of a drum, they might obviously be on the face 125 of a disk replacing the drum, the insulating gap between the said contact rings being arranged at an angle to a radius of the disk. The contact on the electrically actuated member would in this construction be moved 130

radially in accordance with the movement of the control valve or control switch.

When two electric motors are employed as in the last preceding arrangement, instead of using two separate drums and two electrically actuated members as hereinbefore described, we may, as shown in Figs. 5 and 6 employ a single drum or disk A and two electrically actuated members B, B° moving at different speeds, the slower member B° being driven through a form of epicyclic gear by its step-by-step motor B**. When the gun is being trained or elevated slowly the two step-by-step motors angularly displace the spindle b° carrying the directly actuated or faster member B, and also displace the outer spindle B' on which is formed the sun wheel b** of the epicyclic gear. When the gun is being elevated or trained quickly the step-by-step motor B** geared to the outer spindle B' formed with the sun wheel b** (which motor appertains to the transmitting switch that is adapted to transmit large increments of range or bearing) alone moves and causes a displacement of the slower member B° which in turn causes the hereinbefore described relay to operate and cause the drum A to be angularly displaced an amount corresponding to that of the sun wheel b**. In this construction segments are formed in two circles on the face of the drum A. The outer circle of segments a', a², a³, a⁴ and a⁵ appertains to the contact b** of the member B and the inner circle a⁴, a⁵ appertains to the contact B° of the member B°. The contacts b* and B° of the members B and B° respectively bear against a supply ring a³.

Contact plates C*, C** are formed on an extension of the valve stem c and are in contact with fingers c*, c** which are respectively connected to the solenoids D, D'. The said segments a', a², a⁴, a⁵, a⁶, a⁷ and a⁸ are in electrical connection with fingers a**, a²**, a⁴**, a⁶**, a⁷** and a⁸** respectively, that are adapted to engage with the contact plates C*, C**. The supply ring a³ is connected to the source of electric supply. When the member B moves with respect to the drum A it causes for example the segment a⁶ to be electrically connected with the supply ring a³. The solenoid D will accordingly be energized, and the valve C will be moved as hereinbefore described until the finger a⁶** appertaining to the segment a⁶ comes opposite the gap between the two contact plates C*, C**. As the drum A moves to assume its original or neutral position with respect to the member B and the contact a³ becomes electrified, the valve will move until the gap between the plates C*, C** rests upon the corresponding contact a⁶** and will then be completely shut off and the parts brought to rest. By a

suitable separation of the contact fingers, the valve opening may be easily adjusted in proportion to the amount of lag represented by the particular segment in connection with the contact finger. The action of the parts thus approximates to that which occurs in the previously described arrangement with a laterally displaceable contact, but is more intermittent in character owing to the number of partial opening and closing movements of the control valve being limited to the number of contact segments. When only one motor is used as is the case in the construction shown in Fig. 1 the member B° and its circle of segments need not be employed. In this case the teeth of the wheel b** are formed on the spindle b° carrying the member B.

Instead of the hydraulic cylinder relay illustrated in Fig. 1 we may employ other suitable convenient forms of valve opening mechanism the connection of the said mechanism to the contacts on the dial of the drum of the power driven member being similar to that above described.

Fig. 7 shows a constructional form of the means for displacing the motor B* in order to make the necessary corrections in the setting of the member B for varying muzzle velocity or for the separation or distance of the gun from its distant sighting station. The motor B* is mounted on a frame E carried by a bearing E' co-axially with the spindle B' and the drum A. The said frame is provided with a pointer e, and the bearing E' has graduations as shown; by displacing the frame until the pointer e comes opposite the desired graduation the required correction is made. The construction shown in Fig. 7 is, in other respects, similar to that of Fig. 1.

The modification shown in Figs. 5 and 6 of the drawings forms the subject matter of a divisional application, Serial No. 804,165, filed December 2, 1913.

What we claim and desire to secure by Letters Patent of the United States is:—

1. In a control system for power driven mechanism, the combination of a member driven from said mechanism, a member actuated from a distance, a relay under the control of said members, a control device for the power driven mechanism, means for operating said control device from the relay, means whereby relative movement between said members renders the relay operative, and means whereby the movement of said relay consequent on its being rendered operative, renders it again inoperative, the amount of such relay movement varying according to the relative displacement between the two members.
2. In a control system for power driven mechanism, the combination of a member driven from said mechanism, contacts form- 130

- ing part of said member, a relay in electrical connection with said contacts, a member actuated from a distance, a control device for the power driven mechanism, means for operating said control device from the relay, means whereby relative movement between said members completes the electric circuit through the relay, and means whereby the movement of the relay consequent on the completion of the circuit, effects the opening of the circuit, the amount of such relay movement varying according to the relative displacement between the two members.

3. In a control system for power driven mechanism, the combination of a member driven from said mechanism, contacts forming part of said member, a relay in electrical connection with said contacts, a member actuated from a distance, a control device for the power driven mechanism, means for operating said control device from the relay, means whereby relative movement between said members completes the electric circuit through the relay, and means whereby the movement of the relay consequent on the completion of the circuit, causes relative movement between the two members to take place in a direction lateral to the movement of the second mentioned member when actuated from a distance, this relative lateral movement effecting the opening of the circuit through the relay.

4. In a control system for power driven mechanism, the combination of a member driven from said mechanism, contacts forming part of said member, an inclined gap between said contacts, a relay in electrical connection with said contacts, a member actuated from a distance, a control device for the power driven mechanism, means for operating said control device from the relay, means whereby the movement of the second mentioned member out of contact with the insulating gap as a result of the relative displacement between said members completes the electric circuit through the relay, and means whereby the movement of the relay consequent on the completion of the circuit, causes the said second mentioned member to be returned into contact with the insulating gap to open the circuit through the relay.

5. In a control system for power driven mechanism, the combination of a rotary member driven from said mechanism, contacts forming part of said rotary member, an inclined insulating gap between said contacts, a relay in electrical connection with said contacts, a rotary member actuated from a distance, a control device for the power driven mechanism, means for operating said control device from the relay, means whereby the movement of the second mentioned member out of contact with the in-

sulating gap as a result of the relative displacement between said rotary members completes the electric circuit through the relay, and means whereby the movement of the relay consequent on the completion of the circuit causes the said second mentioned member to be returned into contact with the insulating gap to open the circuit through the relay.

6. In a control system for power driven mechanism, the combination of a member driven from said mechanism, contacts forming part of said member, a relay in electrical connection with said contacts, a member actuated from a distance, a hydraulic control device for said power driven mechanism, a hydraulic actuating device for said control device, means forming part of said relay for causing said actuating device to become operative, means whereby the movement of the member out of contact with the insulating gap as a result of the relative displacement between said member and drum completes the electric circuit through the relay, and means whereby the movement of the relay consequent on the completion of the circuit, effects the opening of the circuit through the relay.

7. In a control system for power driven mechanism, the combination of a drum driven thereby, contacts on said drum having an inclined insulating gap between them, a relay in electrical connection with said contacts, a member actuated from a distance, a hydraulic control device for said power driven mechanism, a hydraulic actuating device for said control device, means forming part of said relay for causing said actuating device to become operative, means whereby the movement of the member out of contact with the insulating gap as a result of the relative displacement between said member and drum completes the electric circuit through the relay, and means whereby the movement of the relay consequent on the completion of the circuit, effects the opening of the circuit through the relay by returning the said member into contact with the insulating gap.

8. In a control system for power driven mechanism, the combination of a drum driven thereby, contacts on said drum having an inclined insulating gap between them, a relay in electrical connection with said contacts, a motor controlled from a distance, a member actuated by said motor, a hydraulic control device for said power driven mechanism, a hydraulic actuating device for said control device, means forming part of said relay for causing said actuating device to become operative, means whereby the movement of the said member out of contact with the insulating gap as a result of the relative displacement between said member and drum completes the electric circuit through the relay, and means whereby the movement of the relay consequent on the completion of the circuit, effects the opening

of the circuit through the relay by returning the said member into contact with the inclined insulating gap.

9. In a control system for power driven mechanism, the combination of a drum driven thereby, two contact rings and a supply ring on said drum, an inclined insulating gap between said contact rings, a relay in electrical connection with said contacts, a motor controlled from a distance, a member actuated by said motor, two contacts on said member one of which is in constant engagement with said supply ring, a hydraulic control device for said power driven mechanism, a hydraulic actuating device for said control device, and means forming part of said relay for causing said actuating device to become operative.

10. In a control system for power driven mechanism, the combination of a main member driven thereby, an auxiliary member driven at a different speed, a main member actuated from a distant station, an auxiliary member actuated thereby at a different speed, a relay under the control of said members, a control device for the power driven mechanism, means for operating said control device from the relay, means whereby relative movement between said members renders the relay operative, and means whereby the movement of said relay consequent on its being rendered operative, renders it again inoperative.

11. In a control system for power driven mechanism, the combination of a main member driven thereby, an auxiliary member driven at a different speed, contacts forming part of said members, a relay in electrical connection with said contacts, a main member actuated from a distant station, an auxiliary member actuated thereby at a different speed, a control device for the power driven

mechanism, means for operating said control device from the relay, means whereby relative movement between said main members completes the circuit through the relay, means whereby the auxiliary members maintain the circuit after the relative displacement of the main members reaches a certain amount, and means whereby the movement of the relay effects the opening of the circuit through the relay.

12. In a control system for power driven mechanism, the combination of a main drum driven thereby, an auxiliary drum driven at a different speed, contacts forming part of said drums, a relay in electrical connection with said contacts, a main member actuated from a distant station, an auxiliary member actuated thereby at a different speed, a control device for the power driven mechanism, means for operating said control device from the relay, means whereby relative movement between said main drum and main member completes the circuit through the relay, means whereby the auxiliary drum and auxiliary member maintain the circuit closed after the relative displacement of the main drum and member reaches a certain amount, and means whereby the movement of the relay effects the opening of the circuit through the relay.
